UNITED STATES PATENT OFFICE.

JOHN H. BULLARD AND WILLIAM H. BULLARD, OF ST. PAUL, MINNESOTA.

DESIGN FOR A SPOON, &c.

SPECIFICATION forming part of Design No. 20,841, dated June 16, 1891.

Application filed April 3, 1891. Serial No. 387,565. Term of patent 3½ years.

To all whom it may concern:

Be it known that we, JOHN H. BULLARD and WILLIAM H. BULLARD, both citizens of the United States, residing at St. Paul, Ramsey county, Minnesota, have invented and produced a certain new and original Design for the Handles of Spoons and Similar Articles, of which the following is a specification, reference being had to the accompanying drawing, forming part thereof.

The drawing shows a plan view of a spoon having its handle formed with our new and original design.

The leading features of our design consist of a fort and water-fall. The fort is represented as a circular stone citadel having vertically-slotted port-holes through the walls and arranged at or near the top end of the spoon-handle. On each side are shown flanking walls, and on the ground beneath and in front of the fort is shown a cannon provided with a scroll crossing the cannon. Beneath

this representation is a view of the water-fall fringed by vegetation on each side, with trees and other foliage beyond, the falls extending 25 downward on the handle. The top of the citadel-walls forms the end of the spoon-handle, and the inclosing and flanking walls and the ends of the scroll form the edges of the handle near the end. The edges of the handle from the scroll to the bowl of the spoon are raised or beaded to give it a finished appearance, forming an inclosing border for the view of the falls.

We claim as our invention—

The design for a spoon, substantially as herein shown and described.

In testimony whereof we have hereunto set our hands this 17th day of March, 1891.

JOHN H. BULLARD.

WILLIAM H. BULLARD.

In presence of—

T. D. MERWIN,

A. MAE WELCH,
